UNITED STATES PATENT OFFICE

WILLIAM W. PATTESON, OF CRAWFORD SPRINGS, VIRGINIA.

IMPROVEMENT IN SELF-WAITING TABLES.

Specification forming part of Letters Patent No. 138,687, dated May 6, 1873; application filed February 21, 1873.

To all whom it may concern:

Be it known that I, W. W. PATTESON, of Crawford Springs, in the county of Augusta and in the State of Virginia, have invented certain new and useful Improvements in Dining-Table; and do hereby declare that the following is a full, clear, and exact description thereof, reference being had to the accompanying drawing and to the letters of reference marked thereon making a part of this specification.

The nature of my invention consists in the construction and arrangement of a dining-table with revolving center, as will be herein-after more fully set forth.

In order to enable others skilled in the art to which my invention appertains to make and use the same, I will now proceed to describe its construction and operation, referring to the annexed drawing, in which—

Figure 1 is a side elevation, part in section, of my invention, and Fig. 2 is a plan view of the same.

A A represent four legs constructed in any suitable manner, and connected by means of four cross-bars, B B and C C. The bars B B cross each other in the center, and are let into each other and at each end is a hook or catch, a, to fasten in the legs, in substantially the same manner as an ordinary bed-joint, the upper surfaces of the bars being flush with the upper ends of the legs. The bars C C are connected together in the same manner, and attached by hooks or catches to the legs at a suitable height above the floor. The table-top D is made in two sections hinged together so as to be folded for shipment, and when placed on the frame is fastened to the legs A A by means of hooks b b. In the center of the top D is cut out a circular piece, D¹, which revolves around a vertical center shaft, E, and upon rollers e e placed in recesses on the upper surfaces of the bars B B, around the outer edge of the circular revolving piece D¹, is

a rim, d, extending a short distance upward so that any dishes or plates, &c., placed upon the revolving part D, cannot project beyond the same, and interfere with the articles upon the stationary part of the table. D² represents a smaller disk supported by pillars e above the center of the revolving part D¹, the shaft E passing up through the center of the same. The disk D² may be stationary or removable, as desired; and is intended to be used for salt-stands, glasses, &c., and also to be used as a caster by having suitable hole for the bottles. This revolving structure is turned by means of small knobs i i attached to the rim d of the part D¹.

In the drawing I have represented a fly brush connected to a stem, I, and secured to the vertical shaft E, the said shaft being turned by means of a treadle, cord, and pulley. A rubber band, m, connected to the pulley, causes the shaft to revolve in an opposite direction when the pressure upon the treadle is removed. These devices may be applied to my table, if desired.

When the fly-brush is not required the stem I can be taken out and any suitable ornament put in its place.

Having thus fully described my invention what I claim as new, and desire to secure by Letters Patent, is—

The combination of the bisected and hinged top D, and bisected and hinged revolving top D¹, detachable legs A, and cross-pieces B and C, connected to the legs by the bed-joint hook a, substantially as and for the purposes set forth.

In testimony that I claim the foregoing I have hereunto set my hand this 1st day of February, 1873.

WILLIAM W. PATTESON.
